UNITED STATES PATENT OFFICE

HENRY J. KARP, OF FARIBAULT, MINNESOTA

PENCIL PRINTING DEVICE

Application filed June 30, 1930. Serial No. 464,847.

This invention has for its object to provide a simple and highly efficient pencil printing machine and, to this end, it consists of the novel devices and combinations of devices hereinafter described and defined in the claims.

In the accompanying drawings, which illustrate the invention, like characters indicate like parts throughout the several views.

Referring to the drawings:

Fig. 1 is a plan view of the pencil printing machine;

Fig. 2 is a view in longitudinal vertical section taken on the line 2—2 of Fig. 1;

Figs. 3 and 4 are fragmentary views corresponding to Fig. 1 but showing, the former the pencil ejecting position of the platen and the latter the type inking position thereof;

Fig. 5 is a fragmentary view partly in plan and partly in horizontal section taken on the line 5—5 of Fig. 3;

Fig. 6 is a fragmentary view partly in plan and partly in horizontal section taken on the line 6—6 of Fig. 4; and

Fig. 7 is a fragmentary detail view in section taken on the line 7—7 of Fig. 5 and showing a different type of friction member.

The numeral 8 indicates a flat rectangular bed having at its four corners short supporting legs 9, on its top a way 10 and at its longitudinal center a transverse pencil escape passageway 11. Said way 10 includes a pair of upstanding flanges 12 on the longitudinal edges of the bed 8 and having in their inner faces longitudinally extended grooves 13.

A reciprocating platen 14 is mounted on the way 10 and has on its longitudinal edges tongues 15 slidably mounted in the grooves 13 and support said platen spaced above the bed 8. On the front end of the platen 14 at the transverse center thereof is a handle 16 by which said platen may be reciprocated.

A printing block 17 having on its upper face one or more rows of type 18 is removably mounted in a recessed seat 19, in the bed 8 at the rear end of the pencil escape passageway 11, and releasably held therein by a spring 20. Mounted on the bed 8 rearward of the printing block 17 is a roller inking pad 21. Carried by the platen 14 and ex-

tending rearward thereof is an inking roller 22 arranged to alternately pass over the inking pad 21 and faces of the lines of type 18 during the reciprocatory movement of said platen. From the pad 21 the rollers 22 pick up a supply of ink and applies the same to the faces of the lines of type 18.

A hopper-like magazine 23 for holding a supply of pencils X to be printed is mounted on the platen 14 and extends transversely thereof.

Leading from the bottom of the magazine 23 is a contracted throat 24 for assembling the pencils X, as they are received from said magazine 23, horizontally the one upon the other in a vertical stack supported on the platen 14. The pencils X are successively ejected from the bottom of the throat 24 during the reciprocating movement of the platen 14 by an escapement 25 which includes a slide 26, mounted on the plate 14 under the discharge throat 24, and an escape passageway 27. Said escapement slide 26 has a large central transverse passageway 28 into which projects, from the back of said slide, a pair of lugs 29 spaced transversely of the platen 14. The purpose of these lugs 29 is to contact the passageway 28 to a width to freely receive and hold a single pencil and said lugs further afford means on which the column of pencils X rest during the ejecting of the pencil in the passageway 28.

Depending stop lugs 30 on the end members of the magazine 23 extend into the passageway 28, at the ends of the slide 26, limit both the forward and rearward movements of the slide 26 on the platen 14, and alternately align the passageway 28 with the throat 24 and passageway 27 and also hold said slide against endwise movement, see Fig. 6.

The slide 26 at its ends is arranged to engage upstanding stop pins 31 in the flanges 12 and limit the rearward movement of the slide 26 and position the same with its passageway 28 in registration with the discharge throat 24 to receive the lowermost pencil from the stack. A coiled spring 32 anchored to the platen 14 and attached to the back of the slide 26, intermediate of its ends, yield-

ingly holds said slide in contact with the stop pins 31. When the slide 26 is in contact with the stop pins 31, the escape passageway 27 is closed by the slide 26 and the column of pencils rests on the platen 14. Rearward movement of the platen 14 from its position, as shown in Fig. 6, will bring its escape passageway 27 into alignment with the passageway 28 forward of the lugs 29 and permit the escape of the pencil X in the slide 26 through the passageway 27.

The rearward movement of the platen 14 is limited by the engagement of its tongues 15 with stop blocks 33 in the grooves 13 and held in place by pins 34. Each pencil X passing through the discharge passageway 27 is first positioned longitudinally parallel to the bed 8 and then directed laterally toward the rear of the machine by a pair of deflectors 35 on the under side of the platen 14 and forward of said passageway. These deflectors 35 successively direct the pencils X between cooperating upper and lower raised strips of friction material 36 at each end of the passageway 27 and secured, the former on the under side of the platen 14 and the latter on the bed 8 between the inking pad 21 and printing block 17.

The friction strips 36 may be made from sand paper, as shown in Fig. 5, or ribbed rubber, as shown in Fig. 7. The vertical spacing of the friction strips 36 is such that a pencil is contacted by both thereof so that during the forward movement of the platen 14 the pencil will be moved forward on the bed 8 by rolling and thereby carried over the lines of type 18 and an ink compression made thereon during its rotation. The raised friction strips 36 hold the pencils out of contact with the bed 8 and platen 14 and the width and edgewise spacing of said strips is such that only the end portions of the pencils X are engaged thereby thus causing the pencils to roll thereon at the same peripheral speed at both ends so that the printing thereon is straight longitudinally of the pencil. After a pencil passes over the inking block 17 it is precipitated through the discharge passageway 11.

To hold the pencils X after they are printed and prevent the fresh ink thereon from smearing, said pencils are caught on a rack 37 as they are precipitated through the passageway and held laterally spaced. This rack 37, as shown, is in the form of a flat plate slidably mounted on angle track rails 38, secured to the legs 9 at their inner faces, for movement longitudinally of the bed 8. On the longitudinal edges of the rack 37 are upstanding flanges in which are formed longitudinally spaced teeth 39 of such length as to individually hold the pencils laterally spaced from each other.

A step of forward movement is imparted 65 to the rack 37, which corresponds to the

length of the teeth 39, and during the completion of the rearward movement of the platen 14, by a pair of gravity-held dogs 40 loosely pivoted on the lower ends of upright levers 41 for action on said teeth. The levers 41 are intermediately pivoted to bearings on the under side of the bed 8 with their upper end portions working in slots in said bed and arranged to be engaged by adjustable abutments 42 in the form of screws on the platen 14 which extend rearward therefrom. Compression springs 43, are compressed between abutments on the platen 14 and the upper ends of the levers 41, yieldingly press said levers forward against stops 44 on the flanges 80 12.

During the final rearward movement of the platen 14 the abutments 42 engage the levers 41 and operate the same against the springs 43 to cause the dogs 40 to engage the teeth 39 forward thereof and impart a step of forward movement to the rack 37. The initial forward movement of the platen 14 will carry the abutments 42 away from the lever 41 and allow the springs 43 to return the same to normal positions and at which time the gravity-held dogs 40 will ride over the next rearmost pair of teeth 39 for engagement therewith during the return movement of said platen.

The operation of the pencil printing machine may be briefly described as follows:

A supply of pencils X to be printed is placed in the magazine 23 with their rubber tipped ends all at the left hand end of said magazine, see Fig. 1. It may be assumed that the platen 14 is positioned, as shown in Figs. 1 and 2, and the column of pencils X is resting on the bed 14 with the lowermost pencil in the passageway 28 and with the escape slide 26 held by the spring 32 against the stop pins 31.

To print a pencil the operator takes hold of the handle 16, moves the platen 14 rearward until stopped by the engagement of its tongues 15 with the stop blocks 33. During this movement of the platen 14 the escape slide 26 by its engagement with the stop pins 31 remains stationary and the movement of the platen 14 in respect thereto brings the escape passageway 27 into registration with the passageway 28 and allows the pencil therein to drop into said passageway 27, engages the deflectors 35 and be directed thereby between the upper and lower friction strips 36. During the rearward movement of the platen 14 the escape passageway 27 is moved from under the front member of the escape slide 26 and brought into registration with the passageway 28 and be precipitated therethrough onto the deflectors 35. This rearward movement of the platen 14 carries the magazine 23 rearward so that the throat 24 therein is over the lugs 29 and the column of pencils is supported thereon, see Fig. 3. Said rearward movement of the platen 14 also ac-

tuates the lever 41, as previously described, and causes the dogs 40 by their engagement with certain of the teeth 29 to impart a step of forward movement to the rack 37.

6. At the completion of the rearward movement of the platen 14 the operator, still holding the handle 16, imparts a forward pull thereon to move the platen 14 forward. This forward movement of the platen 14 rolls the 10 pencil X between the friction strips 36 forward over the lines of type 18 and an ink impression is made thereon. The printed pencil in passing over the inking block 17 is precipitated through the passageway 11 and deposited on the rack 37 where it is left to dry. 15 During the forward movement of the platen 14 the inking roller 33 passes over the inking pad 21, picks up a quantity of ink and applies the same to the faces of the lines of type 18. During the rearward movement of the platen 14 from its position, shown in Fig. 2, to its position shown in Fig. 3, the lugs 30 move rearward in the passageway 28.

- 20 During the forward movement of the platen 14 the lugs 30 first move forward in the passageway 28 and then engage the front member of the slide 26 and move the same forward away from the stop pin 31 against the tension of the spring 32 and bring the 25 passageway 28 into alignment with the passageway 27 for the escape of the pencil in the passageway 28 into the passageway 27. During the rearward movement of the platen 14 the inking roller 22 again passes over the face 30 of the type 18 and over the inking pad 21.

- 35 It has been found that the annular beads on the ferrule holding the rubber tip of the pencils cause the pencils to travel slightly faster at one end than at the other so that 40 the printing thereof is not quite true longitudinally of the pencil. To overcome this difficulty corrugated rubber friction strips 45, see Fig. 7, may be substituted for the strips 36. In this type of friction strips the beads 45 on the ferrule will travel in the corrugations thereof or when traveling over the ridges on said strips will compress the same so that the pencil will lie flat.

What I claim is:

- 50 1. In a device of the class described, a bed, a printing block on the bed, a reciprocatory platen mounted over the bed, a magazine on the platen, an escapement actuated by the platen for removing articles from the magazine and delivering the same between the bed and platen to be moved by the platen over the printing block, said escapement comprising a relatively movable slide on the platen and a passageway in the platen, said slide having a passageway, stops relatively fixed in respect to the platen for positioning the slide with its passageway in registration with the magazine, yielding means normally holding the slide against the stops, and means carried by the platen for moving the slide

away from the stops and into a position to close the magazine and bring its passageway into registration with the passageway in the platen.

2. In a device of the class described, a bed, 70 a printing block on the bed, a reciprocatory platen mounted over the bed, a magazine on the platen, opposing friction surfaces on the bed and platen, the friction surface on the bed comprising two edgewise spaced strips 75 one on each side of the printing block, and an escapement actuated by the platen for removing articles from the magazine and delivering the same between said frictional surfaces to be moved by the platen over the 80 printing block.

3. The structure defined in claim 2 in which the friction surfaces are pliable and have corrugations which extend longitudinally in the direction of the movement of the 85 platen.

4. In a device of the class described, a bed, a printing block on the bed, a reciprocatory platen mounted over the bed, a magazine on the platen, two pairs of edgewise spaced 90 raised opposing friction surfaces on the bed and platen, said printing block being between the two friction surfaces on the bed, and an escapement actuated by the platen for removing articles from the magazine and delivering the same between the pairs of opposing friction surfaces to be moved by the platen over the printing block.

5. In a device of the class described, a bed, 100 a printing block on the bed, a reciprocatory platen mounted over the bed, a magazine on the platen, an escapement actuated by the platen for removing articles from the magazine, and a deflector arranged to receive the articles from the escapement during its rearward movement, position the same parallel to the bed and direct the same laterally and rearwardly between the bed and platen to be moved over the printing block by the platen during its forward movement.

6. In a device of the class described, a printing block, a movable platen, a movable rack, and connections operated by the platen for positioning the rack to receive and individually hold articles from the printing 115 mechanism.

7. In a device of the class described, a bed, a printing block on the bed, a reciprocatory platen mounted over the bed and having a passageway, a magazine on the platen having a discharge throat offset from said passageway in the line of travel of the platen, an escapement slide carried by the platen and having a passageway, stop means for positioning the escapement slide with its passageway in registration with said discharge throat, a spring normally holding the escapement slide against the stop means, and further stop means for interrupting the movement of the escapement slide with the platen 120 125 130

during the reciprocatory movement of the platen to cause the discharge throat to move out of registration with the passageway in the escapement slide and bring the passageway in the platen into registration with the passageway in the escapement slide.

8. The structure defined in claim 7 in which the last noted stop means positions the platen with the discharge throat closed by the escapement slide.

9. In a device of the class described, a bed, a printing block on the bed, a reciprocatory platen mounted over the bed and having a passageway, a magazine on the platen having a discharge throat offset rearward from said passageway, an escapement slide mounted on the platen for movement in the line of travel thereof, stop means for positioning the escapement slide with its passageway in registration with the discharge throat and limiting the rearward movement of said slide on the platen, a spring normally holding the escapement slide against said stop means, further stop means on the bed arranged to be engaged by the escapement slide and interrupt the movement thereof with the platen during its rearward movement, and still further stop means arranged to limit the rearward movement of the platen and position the same with its passageway in registration with the passageway in the escapement slide and with the magazine positioned with the discharge throat closed by the escapement slide.

25 In testimony whereof I affix my signature.
HENRY J. KARP.
